UNITED STATES PATENT OFFICE.

PAUL A. DRUCKLER, OF NEW YORK, N. Y., ASSIGNOR TO NEW YORK CIGARETTE MACHINE COMPANY, OF NEW YORK, N. Y., A CORPORATION OF NEW YORK.

MACHINE FOR FINISHING CIGARETTE-SEAMS.

1,152,717.

Specification of Letters Patent. Patented Sept. 7, 1915.

Original application filed March 18, 1913, Serial No. 755,104. Divided and this application filed August 2, 1913. Serial No. 722,607.

To all whom it may concern:

Be it known that I, PAUL A. DRUCKLER, a citizen of the United States, and a resident of New York, county of New York, 5 and State of New York, and whose post-office address is 14 Park Place, New York city, county of New York, and State of New York, pray that Letters Patent may be granted to me for Improvements in Machines for Finishing Cigarette-Seams, of which the following is a specification.

My present application which is a division of an application filed by me on the 18th day of March, 1913, Serial No. 755,104, to 15 which cross reference is made relates to a certain novel construction to be used for the purpose of finishing the seam in a pasted cigarette rod.

The particular type of device to which my present invention is directed embodies the idea of a presser finger or blade, preferably having a contact surface where it bears upon the seam of a little more than the width of the seam, so that the pressure 20 exerted by the blade on the seam will be substantially coextensive with its width, and additionally wherein the pressure of the blade gradually increases as the movement of the cigarette rod under the presser finger 25 progresses. Such a type of seam finishing device is shown and described in the application for Letters Patent which I filed jointly with Daniel Hemming on the 31st day of May, 1912, Serial No. 700,609.

It is to a device of this class which my present invention relates, and it consists in 30 novel structure or embodiment of the underlying ideas set forth in said application, which will be hereinafter more fully described, and finally set forth in the claims appended hereto.

In the drawing forming part of this application, Figure 1 is a perspective view of a portion of a cigarette making machine, 40 and a like view of my improved seaming device secured in operative position thereto. Fig. 2 is a plan view. Fig. 3 is a side elevation of the same. Fig. 4 is a longitudinal sectional elevation, the section being taken on the plane of the line *a*, *a* of Fig. 2. Fig. 5 is a transverse sectional elevation on the plane of the line *b*, *b*, of Fig. 3, looking in the direction of the arrows.

Like reference characters indicate similar parts throughout the several views. 55

The embodiment of my invention, as shown herein, may be readily adapted to a conventionally constructed cigarette making machine. So far as my present improvements are concerned, the only essential 60 parts of the cigarette making machine that it is necessary to describe here is the conveyer tape which conveys the cigarette rod to the seaming and finishing device, a tube through which the tape passes after or during the time the lap of the seam has been 65 formed and pasted, means for propelling the tape and cigarette rod, and suitable supports for the said devices. I shall describe only that much of the cigarette making machine which is embraced in the foregoing statement, as I deem that to be sufficient for the purpose of illustrating the application 70 of my invention.

At 1 is a portion of the bed of a cigarette 75 making machine. At 2 is a plate constituting the terminal portion of the grooves through which the conveyer or propelling tape and the cigarette rod moves. Suitable devices may be used for detachably securing the parts together as the set-screw 2^a. In devices of this kind, there is usually in advance of the terminal of the grooves, means for lapping and pasting the edges of 80 the paper surrounding the tobacco core, and 85 for guiding the pasted rod and tape through the terminal block and to the ironing or finishing means.

The cigarette rod, comprises the tobacco 90 filler 3 and the paper covering 4 having the overlapped edges 5 and 6. At 7 is the propelling wheel about which the conveyer tape 8 passes, and which acts as the means for propelling the tape and cigarette rod through the machine. The edges of the 95 tape, when embracing the cigarette rod do not meet, so that when the rod and encircling tape pass the pasting and finishing devices, access to the seam of the rod may be had between their edges. The foregoing 100 are conventional parts, and may be constructed as shown, or modified to suit the particular requirements.

The presser blade comprises a block 26^a, which in cross section is in the shape of a 105 truncated pyramid, its operative or contact

surface 27^a (shown diagrammatically in Fig. 11) being substantially of the lateral dimensions of the seam of the cigarette rod. The blade 26^a is removably and detachably secured to the plate 2 by providing the latter with a short recess 51 (Fig. 4) and the former with the lug or projection 52 which is let into the recess, this form of connection being had mainly for the purpose of preventing the blade from becoming laterally displaced, at the same time providing a movable connection of it with the supporting block 2.

At 53 is a flat bow-spring having flattened ends 54, 55, the end 54 being secured to the flat top 56 of the blade 26^a adjacent its toe portion 29, the end 55 being provided with a hole through which is passed the threaded stem 57 of the fastening screw 58, which has a flange 59 bearing on top of the end 55 of the spring, the plate 2 having a tapped hole receiving the threaded stem 57. By means of these devices the spring can be readily and detachably secured to the plate 2 or any other desired portion of the machine.

The spring 53 causes the blade 26^a to bear down on the seam with a yielding pressure and gives to it the desired angle of inclination, as indicated by the dotted line α in Figs. 3 and 4. It will be noted that the heel 28 of the blade is capable of yielding and exerting a relatively light pressure upon the seam of the rod as the latter emerges from the controlling or guiding tube, and that this pressure increases with the amount of pressure exerted by the spring 53, the latter giving the presser blade the desired amount

of downward inclination at the toe portion 29.

From the foregoing, it will be noted that my invention may be variously modified, within the scope of the appended claims, without departing from its spirit.

I claim:

1. In a machine for finishing cigarette seams, the combination with a support with a recess therein, a presser blade, a projection from one end of the blade received in said recess, and a spring secured to said support and to said blade. 45

2. In a machine for finishing cigarette seams, the combination with the presser blade, a support therefor, a flat spring secured to said support at one end and to the presser blade at the other end. 50

3. In a machine for finishing cigarette seams, the combination with a support, a presser blade movably secured thereto, a flat spring secured at one end to said support, and at the other end to the presser blade adjacent the free end of said blade. 55

4. In a machine for finishing cigarette seams, the combination with a support with an upwardly extending recess formed therein, a presser blade having a projection extending into said recess, and a spring connecting the support and presser blade. 60

Signed at the city, county and State of New York, this 31st day of July, 1913.

PAUL A. DRUCKLIEB.
